CLAIM

The ornamental design for an oil burning candle apparatus, as shown and described.

DESCRIPTION

FIG. 1 is a top and front perspective view of a first embodiment of an oil burning candle apparatus.
FIG. 2 is a front view of the oil burning candle apparatus of FIG. 1.
FIG. 3 is a side view of the oil burning candle apparatus of FIG. 1.
FIG. 4 is a top view of the oil burning candle apparatus of FIG. 1.
FIG. 5 is a bottom view of the oil burning candle apparatus of FIG. 1.
FIG. 6 is a top and front perspective view of a second embodiment of an oil burning candle apparatus.
FIG. 7 is a front view of the oil burning candle apparatus of FIG. 6.
FIG. 8 is a side view of the oil burning candle apparatus of FIG. 6.
FIG. 9 is a top view of the oil burning candle apparatus of FIG. 6.
FIG. 10 is a bottom view of the oil burning candle apparatus of FIG. 6.
FIG. 11 is a top and front perspective view of a third embodiment of an oil burning candle apparatus.
FIG. 12 is a front view of the oil burning candle apparatus of FIG. 11.
FIG. 13 is a side view of the oil burning candle apparatus of FIG. 11.
FIG. 14 is a top view of the oil burning candle apparatus of FIG. 11.
FIG. 15 is a bottom view of the oil burning candle apparatus of FIG. 11.
FIG. 16 is a top and front perspective view of a fourth embodiment of an oil burning candle apparatus.
FIG. 17 is a front view of the oil burning candle apparatus of FIG. 16.
FIG. 18 is a side view of the oil burning candle apparatus of FIG. 16.
FIG. 19 is a top view of the oil burning candle apparatus of FIG. 16.
FIG. 20 is a bottom view of the oil burning candle apparatus of FIG. 16.
FIG. 21 is a top and front perspective view of a fifth embodiment of an oil burning candle apparatus.
FIG. 22 is a front view of the oil burning candle apparatus of FIG. 21.
FIG. 23 is a side view of the oil burning candle apparatus of FIG. 21.
FIG. 24 is a top view of the oil burning candle apparatus of FIG. 21.

FIG. 25 is a bottom view of the oil burning candle apparatus of FIG. 21.

FIG. 26 is a top and front perspective view of a sixth embodiment of an oil burning candle apparatus.

FIG. 27 is a front view of the oil burning candle apparatus of FIG. 26.

FIG. 28 is a side view of the oil burning candle apparatus of FIG. 26.

FIG. 29 is a top view of the oil burning candle apparatus of FIG. 26.

FIG. 30 is a bottom view of the oil burning candle apparatus of FIG. 26.

FIG. 31 is a top and front perspective view of a seventh embodiment of an oil burning candle apparatus.

FIG. 32 is a front view of the oil burning candle apparatus of FIG. 31.

FIG. 33 is a side view of the oil burning candle apparatus of FIG. 31.

FIG. 34 is a top view of the oil burning candle apparatus of FIG. 31.

FIG. 35 is a bottom view of the oil burning candle apparatus of FIG. 31.

FIG. 36 is a top and front perspective view of an eighth embodiment of an oil burning candle apparatus.

FIG. 37 is a front view of the oil burning candle apparatus of FIG. 36.

FIG. 38 is a side view of the oil burning candle apparatus of FIG. 36.

FIG. 39 is a top view of the oil burning candle apparatus of FIG. 36.

FIG. 40 is a bottom view of the oil burning candle apparatus of FIG. 36.

FIG. 41 is a top and front perspective view of a ninth embodiment of an oil burning candle apparatus.
FIG. 42 is a front view of the oil burning candle apparatus of FIG. 41.

FIG. 43 is a side view of the oil burning candle apparatus of FIG. 41.

FIG. 44 is a top view of the oil burning candle apparatus of FIG. 41.

FIG. 45 is a bottom view of the oil burning candle apparatus of FIG. 41.

FIG. 46 is a top and front perspective view of a tenth embodiment of an oil burning candle apparatus.

FIG. 47 is a front view of the oil burning candle apparatus of FIG. 46.

FIG. 48 is a side view of the oil burning candle apparatus of FIG. 46.

FIG. 49 is a top view of the oil burning candle apparatus of FIG. 46; and,

FIG. 50 is a bottom view of the oil burning candle apparatus of FIG. 46.

The broken lines in the drawings represent portions of the oil burning candle apparatus that form no part of the claimed design.
